[57] CLAIM

The ornamental design for a combined lamp and turn
signal for snow plows and the like, as shown and de-
scribed.

DESCRIPTION

FIG. 1 is a front elevational view of a combined head-
light lamp and turn signal lamp for snow plows and the
like embodying our novel design.

FIG. 2 is a plan view of the same.

FIG. 3 is an end view of the same taken from the left as
viewed in FIG. 2.

FIG. 4 is an end view of the same taken from the right
as viewed in FIG. 2.

FIG. 1

FIG. 2

FIG. 3
